UNITED STATES PATENT OFFICE.

JOSEPH BIJUR, OF NEW YORK, N. Y., ASSIGNOR TO THE SAFETY CAR HEATING & LIGHTING COMPANY, OF NEW YORK, N. Y., A CORPORATION OF NEW JERSEY.

ELECTRIC REGULATOR.

1,260,995.

Specification of Letters Patent. Patented Mar. 26, 1918.

Application filed July 1, 1910. Serial No. 569,936.

To all whom it may concern:

Be it known that I, JOSEPH BIJUR, a citizen of the United States, residing at New York, in the county of New York and State 5 of New York, have invented certain new and useful Improvements in Electric Regulators, of which the following is a full, clear, and exact description, such as will enable others skilled in the art to which it 10 appertains to make and use the same.

This invention relates to electrical regulating apparatus. One of the objects thereof is to provide reliable, efficient and accurate electrical regulating apparatus. Another 15 object is to provide apparatus of the above type in which extreme variation in a resistance element is efficiently utilized. Another object is to provide in regulating apparatus, simple and practical means for 20 substantially eliminating the effect of variations in temperature. Another object is to provide regulating apparatus of the character first mentioned of compact and self-contained construction. Other objects will 25 be in part obvious and in part pointed out hereinafter.

The invention accordingly consists in the features of construction, combinations of elements and arrangement of parts which 30 will be exemplified in the construction hereinafter set forth, and the scope of the application of which will be indicated in the following claims.

In the accompanying drawings, wherein 35 is shown one of various possible embodiments of this invention,

Figure 1 is a diagrammatic plan of the same;

Fig. 2 is a plan of a pilot regulator;

Fig. 3 is a side elevation of the same;

Fig. 4 is a front elevation of a main regulator;

Fig. 5 is a plan view of the same;

Fig. 6 is an end elevation of the same;

45 Figs. 6^a and 6^b are views of details of the apparatus;

Figs. 7 and 8 are curves illustrating certain features of the action of the apparatus.

Similar reference characters refer to similar parts throughout the several views of the drawings.

Referring now in detail to Fig. 1 of the drawings, there is shown a generator 1 hav-

ing a shunt field 2 across the mains 3 and 4 of which is bridged a secondary battery 5. 55 Suitable switches 6 and 7 are provided as in the main 3, and the former may be of an automatic construction known in the art in a similar relation. Serially connected in the main 4 is a variable resistance medium 8, hereinafter described in detail, and bridged across the mains at a point beyond this resistance are lamps or other translating devices 9. Also bridged across the mains and at a point adjacent the lamps 9 is a voltage-coil 10 having connected in its circuit a resistance element 11, hereinafter referred to 60 in detail.

As conducive to a clearer understanding of the details of this invention, it may be 70 noted at this point that the field of the solenoid 10, whose field varies with the voltage across the mains adjacent the lamps, is utilized to control the current flowing through a local circuit 12, also bridged 75 across the mains and having disposed therein the magnet 13. The latter magnet by suitable means appropriately varies the resistance of the medium 8 to accord with any tendency to abnormalities of the voltage 80 upon the lamps and by this variation of the potential drop in the main 4, the lamp-voltage is held constant to a nice degree.

Recurring to the solenoid 10, it is to be noted that the field of this element controls 85 the position of a movable core 14, which, acting through the knife-edge 15, moves a lever 16. This lever, one end of which enters the core 14 beneath the knife-edge 15, comprises a pair of arms 17 and 18 clamped 90 about a rocking spindle 19. The ends of the spindle are provided with a downwardly extending edge, as indicated at 20, and these edges rest upon bearings 21 mounted in casings 22 upon the frame 23. This frame is 95 secured to a panel 24 supporting the solenoid 10 through the frame 25. In frame 23 there is formed a suitable bracket 26, for the arm 17, provided with set-screws 27 to limit the range of movement of the arm. 100 Arm 18 is jointed to a rod 28 at its free end, the latter member leading to a suitable dashpot 29. Also connected to the arm 18 is a spring 30, the tension of which is adjustable by the threaded pin 31 and knurled nut 32. 105 These several moving parts are so formed

and related that their center of gravity, collectively considered, is substantially in the axis about which they swing, and, hence, they are not only unaffected by jarring or vibration, but tend to maintain, in so far as gravity is concerned, any position in which they may be placed.

Formed upon the arm 17 is a depending lug or arm 33, to which is pivoted a link 34 10 swung from the frame by the pairs of parallel links 35 and connected with a movable pressure-plate 36. Adjustably mounted opposite this plate in the frame 23 is a similar plate 37, the position of which is governed by 15 a suitable threaded shank 38. Between these plates are mounted a set of thin upright carbon disks 39, contacting one with another, and suitable means are provided to make connection to these disks serially in the circuit 12. As these disks are compressed by 20 the downward swinging of the arm 17, due to an increase of field strength of the solenoid 10, their aggregate resistance is reduced and the current in the circuit 12 increased in substantial 25 accordance therewith. The mechanical resistance to compression of these disks is of a low order owing to their small size, loose contact and upright disposition, and the force exerted by the core of the solenoid 30 10 is multiplied several times by the leverage due to the above arrangement and proportioning of parts. For this reason, assuming the various forces to be balanced with a normal voltage across the lamps, any slight 35 variation in this potential difference will be highly effective in its variation of the resistance of the carbon-disks, and a small departure from normal voltage will generally cause a continuous compression or compression 40 of the disks until they act through the regulating apparatus, later described, to restore normal voltage across the lamps and a normal field strength of the solenoid 10. The action of this pilot is thus rendered extremely 45 sensitive, and by a proper conformation and adjustment of the spring 30 it can be made to hold substantially any position with normal voltage across the mains.

The resistance element 11 is formed of an alloy of such composition that its electrical resistance is substantially constant throughout a large range of temperatures, and this resistance is taken of such value that nearly the entire fall in potential in the branch circuit, comprising the solenoid 10, occurs at this point. In this manner, a large proportion of the C²R heating occurs in the element 11, rather than in the solenoid 10, which is of a relatively low resistance, and this heating effect does not vary the current by which it is caused. It will be noted, however, that with any given change in voltage across the lamps, there will be an exactly corresponding proportional change in potential difference at the terminals of the solenoid, and,

consequently, a like variation in its field strength. For example, assuming that the voltage across the lamps is thirty and with twenty-five volts drop in the resistance element 11 there is substantially five volts 70 across the solenoid; if now there is a given change of voltage across the lamps, there is only one-sixth of this change across the solenoid, but as its potential difference at its terminals is only five volts, instead of thirty, 75 the effect of this variation in voltage is the same as though the solenoid were directly connected, and, yet, the inaccuracy, due to variation in temperature, is eliminated as the heating in the solenoid is insignificant. To 80 form the entire solenoid of the above alloy, having sufficient ampere turns, would occasion a large loss in cheapness and compactness.

Considering now the main regulator, 85 shown in Figs. 4, 5 and 6, it is to be noted that the magnet 13 is of the two-pole type, having separate windings upon each pole, and these poles 40 and 41 are provided with rounded, tapering ends. Coacting with this magnet, which is mounted adjacent a frame 42, is an armature 43 secured to a frame 44 pivotally connected at 45 to main frame 42. This armature is provided with a pair of openings 46 adapted to permit the entry of 90 the rounded poles 40 and 41, and the curve of the poles, as well as the walls of the openings, is so formed that with a given field strength of the magnet, the pull exerted upon the armature increases uniformly at a 95 slight rate as the armature approaches the poles. This effect is gained by so forming the parts that as the lines of force through the armature multiply upon its approach to the poles, they decrease in effectiveness to 100 nearly the same extent owing to their lateral tension rather than direct pull in the direction of movement of the armature. The above is expressed in the terminology of 105 commonly accepted theories of magnetic action and will, it is believed, make clear that any variation in pull of the magnet 13 upon its armature is due substantially to a corresponding variation in its field strength. Connected with a projection 47 upon the 110 swinging armature 43, by means of links 48, is a forked crank 49 having secured thereon a stepped contact-bar 50 for a purpose herein-after described. Pivotally mounted upon the supporting pin 51, between the portions 115 of the crank 49, is a link 52 which curves about a shaft 53, the latter being mounted in bearings 54 upon the frame 42 and having a crank 49 pinned thereon. This link extends throughout the length of the apparatus and is connected with a short rod 55 by a pivot-pin 56. This pivot-pin has a loose bearing in the link 52 and, accordingly, permits to the rod 55 a slight swinging movement in any direction, thus performing 120 125 130

the functions of a universal joint. Rod 55 passes loosely through a pressure-plate 57 and has threaded thereon a heavy adjusting nut 58, which bears upon an insulated collar 59 formed on the pressure-plate.

At the end of the frame 42 adjacent the shaft 53, is formed a stationary pressure-plate 60 and between this plate and the plate 57 are three sets 61 of contacting carbon disks symmetrically grouped about the actuating link 52. These disks are arranged with their contacting surfaces substantially upright and are separated by the copper plates or taps 62 into four sections, the several sets being serially connected in main 4 in parallel one with another.

It may be noted at this point that as the armature 43 swings downwardly, it rotates the shaft 53 and exerts a thrust upon the link 52, which is transmitted through the rod 55 and nut 58, to relieve the pressure upon the plate 57, which is thus permitted to swing outwardly upon the loosely connected links 63 by which it is suspended. It may also be noted that by an adjustment of the nut 58 the pressure upon the sets of disks is varied without varying the position of the armature 43.

Mounted on shaft 53 is a crank 64 having an arm 65 which leads by a pivotal connection 66 to a dash-pot 67 of any ordinary or well known construction. This crank is provided with an arm 68 extending toward the pressure-plate 57, which is so mounted, proportioned and adjusted as to balance the weight of the various parts, connected with the shaft 53, in their various positions and maintain the center of gravity of the several weights acting upon the shaft substantially in its axis.

Formed in crank 64 is a slot 69 concentric with respect to the shaft 53 and adjustably mounted in this slot, as by means of the nut 70, is a link 71 leading to a spring 72, the tension of which is adjusted by the eye-bolt 73 passing through the frame 42. This arrangement of parts permits not only adjustment of the tension of the spring, which is carefully proportioned to perform its functions, but adjustment of its effective pulling arm with respect to the shaft 53, and consequently of the rate of variation of its turning movement as the shaft rotates from any given position.

The spring 72 tends to rotate the shaft 53 in opposition to the attractive force of the magnet 13, and acting through the crank 49 and link 52, which form in effect a toggle, tends to compress the several sets of carbon disks, the pressure upon all sets being equalized by the universal joint connection of the link with rod 55. These disks are accordingly compressed or released in accordance with the preponderance of turning movement of the spring 72 or magnet 13 and

travel freely and unaffected by gravity being held in alinement by means of the several rods 74 extending from the frame 42 to the plate 60 and provided with insulating sleeves 75.

70

A suitable electrical connection is provided from main 4 to contact-bar 50, as shown in Fig. 1, and the several stepped contacts of this element coat with the spring-brushes 76, 77, 78 and 79. These brushes 75, 79, 78 and 77 are respectively connected with the successive plates 62 and brush 76 is in connection with the main 4.

As the contact bar 50 swings upwardly under the influence of the spring 72 and approaches a position of maximum pressure with the toggle substantially on its center, the spring-brush 79 is first met, providing a dead short-circuit about the first section of the several sets of disks, and thus reducing the residual resistance of the medium. Swinging farther the contact-brush 78 is engaged, 79 being bent back, cutting out another section, and in this manner the entire residual resistance of the medium at maximum compression is eliminated by a metallic short-circuit about the same. The rapidly increasing pressure exerted by these short-circuiting brushes as they are successively met and bent back to permit the next contact 95 to be made acts directly to oppose rotation of the shaft 53 and is utilized as hereinafter described.

In order to avoid the chance of ambiguity in the meaning of certain expressions used throughout this description and following claims, it may be noted at this point that the term "plate" or "pressure-plate" is used broadly as definitive of any element through which pressure may be exerted upon a variable resistance medium, and by the expression "collective resistance to compression," or the like, with reference to contacting resistance elements, is meant their resistance to pressure due to their contacting one with another and gaining support one from another as distinguished from the relatively insignificant mechanical resistance which they exert when loosely disposed, due probably to their tilting against one another. It 110 may also be noted that by the central position of the toggle, or a position on its center, is meant that position in which the axes of its two component members are substantially in alinement.

120

As preliminary to a discussion of the operation of this apparatus, it may be noted that the mechanical resistance to compression of a pressure-controlled variable resistance medium increases at an increasing rate as the compression progresses. To illustrate this, if a pressure of ten pounds is required to compress the medium for one-tenth of an inch, twenty pounds will not suffice to compress it two-tenths of an inch. 130

The pressure required in this case may be thirty pounds, and to compress it a further tenth, it may require one hundred pounds or more. The above is merely illustrative of the fact that the curve of compression, with compressive force as ordinates and linear compression as abscissæ is upwardly concaved. It may also be noted that the curve representing the force exerted by a toggle as it approaches its center, with a uniform turning moment, is likewise upwardly concaved, and these curves correspond closely, except as the toggle comes upon its center, when its force is theoretically infinity, and accordingly increases at this stage faster than the mechanical resistance of the carbons. Thus, with a uniform turning moment of the shaft 53, the pressure exerted upon the carbons increases at an increasing rate and their resistance to compression likewise increases at an increasing rate. The toggle is thus used to compensate for the accelerating resistance to compression of the resistance medium, and, hence, the resistance to turning of the shaft 53 exerted by the carbons through the toggle is substantially constant, although it increases to a slight degree throughout most of the range and decreases more sharply at the end of maximum compression, due to the above noted effect of the toggle. Referring to Fig. 7 of the drawings, the curve A—B is illustrative of the turning moment required for a uniform rate of compression of the resistance medium; the abscissæ being the compression of the medium and the ordinates the torque or the turning moment required to affect it. The drop of the curve at C is due to absence of collective resistance to compression of the carbons, and the drop at B due to the effect of the toggle. The latter drop is compensated for by the resistance to the turning of the shaft effected by the successive deformation of the short-circuiting brushes, above noted, and, hence, the resultant of the various forces, aside from the magnet, acting to rotate to relieve pressure upon the carbons, is indicated by the curve A—D.

Considering the forces tending to turn the shaft in the opposite direction, the weight of all parts may be disregarded, for they are balanced, as above noted, and the dash-pot is, of course, merely a retarding, rather than an active, force. The spring 72 as the compression progresses loses a portion of its tractive force, due to the release of tension, but this is partially compensated for by the increase of the effective arm through which it acts on the shaft 53. These errors would exactly offset one another, theoretically considered, only with the crank at forty-five degrees to the line of pull on the spring, but, in practice, the parts are so arranged that the turning moment of the spring is substantially constant or slightly falling. Hence,

in Fig. 7, the dotted curve E—F represents the effective turning moment of the spring. The difference between these resultant torques, indicated by the vertical cross-hatching, is the turning moment which must be exerted by the magnet to vary the pressure from total compression to total release and the curve G—H Fig. 8, represents this torque. The slight decrease in the effective arm through the crank 49 is substantially compensated for by the slight increase in the pull due to position of armature, and, hence, with a magnetic field strength, and consequently with a strength of current in the magnet, which increases continually as indicated by the curve G—H Fig. 8, there will be a substantially uniform compression of the variable resistance medium. Hence, for any current value in the magnet 13, there is a fixed and definite position which the regulating apparatus will assume and a fixed and definite resistance which is inserted serially in the main 4. In this manner the chance of "hunting" of the apparatus is done away with and its action is rendered thoroughly reliable, accurate and effective. It is to be pointed out in this connection that by reason of the grouping of the sets of resistance members about the actuating link 52, which, in so far as certain broad features of this invention are concerned, may be replaced by any actuating element, there is attained a compactness of structure and directness of pull which contribute materially to the advantages and efficient action of the apparatus.

It may also be noted that by reason of the arrangement and proportioning of the parts, the pressure upon the sets of carbon disks may be reduced to any desired point, and, hence, the range of variation in resistance increased. As above noted, there is a certain range of resistance in media, comprising a plurality of substantially upright contacting members, which extends beyond the point at which they collectively resist compression. This range is extremely valuable and, yet, in ordinary regulating apparatus is unused, as the actuating means are not adapted to hold the compressing members in a position beyond that at which the disks are in full contact with and pressing against one another. It may also be noted that by the use of apparatus such as that herein described, an extreme degree of compression upon the resistance medium is obtainable and the parts are, in fact, compressed to such an extent that the contact resistance may be substantially eliminated or reduced below the value of the internal resistance of the disks.

Briefly stated, the operation of the entire apparatus is as follows:—Upon the voltage across the mains varying from the desired normal value a corresponding change will

occur in the field strength of the solenoid 10, thus inducing a proportionate alteration in the electrical resistance value of the group of carbon disks 39. This action will 5 occasion a proportionate change in the current flowing through conductor 12 and in the field strength of the magnet 13, the field strength of the latter being increased with a tendency to abnormally high voltage or 10 weakened when the voltage tends to fall below normal. The variation in field strength of magnet 13 will occasion a movement of the armature 43, which, acting through the means above described, will increase or decrease the resistance of the main 15 regulator and change the potential drop therein to precisely such extent as is necessary to bring the voltage impressed upon the lamps to normal value. The action of 20 these parts is so sensitive and rapid that there will be no substantial change in the voltage of the lamps as the slightest tendency to change will immediately remedy itself.

25 It will thus be seen that there is provided apparatus in which the several objects of this invention are achieved, and which is sensitive, accurate and reliable in action, of simple, compact and durable construction 30 and well adapted to meet the conditions of the hardest practical use.

As many changes could be made in the above construction and many apparently widely different embodiments of this invention could be made without departing from the scope thereof, it is intended that all matter contained in the above description or shown in the accompanying drawings shall be interpreted as illustrative and not in a 40 limiting sense.

Having described my invention, what I claim as new and desire to secure by Letters Patent is:

1. In regulating apparatus, in combination, a variable resistance medium comprising a plurality of sets of contacting members, and current-controlled means adapted to vary the compression of said medium at a uniform rate with a substantially uniform 45 rate of variation of current throughout the range of collective resistance to compression offered by said members, and to reduce the compression of said medium beyond said range.

50 2. In regulating apparatus, in combination, pressure controlled variable resistance media, each comprising a plurality of contacting members, a pressure device extending over the ends of said media, and actuating means about which said media are 55 grouped operatively related to said pressure device to compress said media, said actuating means being current-controlled and adapted to vary the compression of said media at a uniform rate with a substantially

uniform rate of variation of current throughout the range of collective resistance to compression offered by said members, and to reduce the compression of said media beyond said range.

70

3. In regulating apparatus, in combination, a plurality of sets of contacting members, each set being arranged with its members in substantially upright position, pressure means extending over said several sets, 75 connections whereby the pressure upon said sets is equalized, means adapted to reduce the pressure upon said members beyond the point at which they collectively offer resistance to said compression, said means comprising a toggle adapted to increase the pressure as it approaches central position and circuit-closing means upon the apparatus formed to oppose movement of said toggle.

85

4. In regulating apparatus, in combination, a plurality of pressure-controlled variable resistance media, a relatively fixed member against which said media abut at one end, a movable pressure member extending over said several media, a member having a universal joint connection with said pressure member and adapted simultaneously to exert equal pressure upon said media and electrically controlled means 90 adapted to actuate said last member.

90

5. In regulating apparatus, in combination, variable resistance media, each comprising a plurality of contacting members, a pressure plate extending over the ends of 100 said media, and provided with connections to equalize pressure thereon, and current-controlled means comprising a toggle having a continuous link extending between said media for controlling said plate to vary 105 the compression of said media at a uniform rate with a substantially uniform rate of variation of current throughout the range of collective resistance to compression offered by said members.

110

6. In regulating apparatus, in combination, a plurality of sets of contacting members, each set being arranged with its members in substantially upright position, a pressure plate extending over said sets, a 115 member extending between said sets for operating said pressure plate, a connection between said plate and said member permitting movement of said plate to equalize pressure upon said sets, electrically controlled actuating means operatively related to said member to compress said sets and also to reduce the pressure upon said sets beyond the point at which they collectively offer resistance to compression.

120

7. In regulating apparatus, in combination, a plurality of sets of contacting members, each set being arranged with its members in substantially upright position, pressure means extending over said several sets, 130

connections whereby the pressure upon said sets is equalized, and current-controlled means extending between said sets and operatively related to said pressure means to

- 5 vary the compression of said members at a uniform rate with a substantially uniform rate of variation of current throughout the range of collective resistance to compression offered by said members, and to reduce the 10 compression of said members beyond said range.

8. In regulating apparatus, in combination, a plurality of sets of contacting members, each set being arranged with its members in substantially upright position, a pressure plate extending over the ends of said sets, and current-controlled means having a universal joint connection with said pressure plate and extending between said 15 sets and adapted to move said plate to compress said sets.

9. In regulating apparatus, in combination, a plurality of sets of contacting members, each set being arranged with its members in substantially upright position, and current-controlled means extending between said sets for varying the compression of said members at a uniform rate with a substantially uniform rate of variation of current 20 throughout the range of collective resistance to compression offered by said members, and for reducing the compression of said members beyond said range.

10. In regulating apparatus, in combination, a plurality of pressure-controlled variable resistance media, a pressure plate extending over the ends of said media, and current-controlled means extending between said media and having a universal joint 25 connection with said pressure plate and adapted to move said plate to compress said media.

11. In regulating apparatus, in combination, a plurality of sets of contacting members, a pressure plate extending over the ends of said sets, and current-controlled means having a universal joint connection with said pressure plate for controlling said plate to vary the pressure of said sets at a uniform rate with a substantially uniform 30 rate of variation of current throughout the range of collective resistance to compression offered by said members.

12. In regulating apparatus, in combination, a plurality of sets of contacting members, each set being arranged with its members in substantially upright position, a pressure plate extending over the ends of said sets, and current-controlled means comprising a toggle having a continuous link 35 extending between said sets and co-acting with said pressure plate to vary the compression of said sets at a uniform rate with a substantially uniform rate of variation of current throughout the range of collective resistance to compression 40 offered by said members.

lective resistance to compression offered by said members, and to reduce the pressure on said sets beyond the said range.

13. In regulating apparatus, in combination, a pressure-controlled variable resistance medium comprising a plurality of contacting members formed and constituted to resist mechanical pressure at an increasing rate as the compression progresses, means adapted to vary the pressure thereon 75 at a different rate as the compression progresses, and electro-magnetic means operatively related to said medium and adapted with a constant rate of increase of current therein to compensate for the difference in 80 said rates and vary the compression of said medium at a constant rate throughout the range of collective resistance to compression offered by said members, and to reduce compression of said members beyond said range. 85

14. In regulating apparatus, in combination, a pressure-controlled variable resistance medium comprising a plurality of contacting members resisting mechanical pressure at an increasing rate as compression 90 thereof progresses, and electrically controlled means adapted to vary the pressure upon said medium at a different rate as compression progresses, said medium and said means being so formed relatively to each 95 other that the pressure exerted by said means upon said medium is substantially equal to the resistance to compression offered by said medium throughout the range of collective resistance to compression offered by the component members of said medium, said means also being adapted to reduce the compression of said medium beyond said range. 100

15. In regulating apparatus, in combination, a plurality of pressure-controlled variable resistance media, a pressure plate extending over the ends of said media, and current-controlled means extending between said media and having a universal joint connection with said pressure plate and adapted 105 to move said plate to compress said media. 110

16. In regulating apparatus, in combination, a plurality of sets of contacting members, a pressure plate extending over the 115 ends of said sets, and current-controlled means having a universal joint connection with said pressure plate for controlling said plate to vary the pressure of said sets at a uniform rate with a substantially uniform 120 rate of variation of current throughout the range of collective resistance to compression offered by said members.

17. Regulating apparatus comprising, in combination, a pressure-controlled variable 125 resistance medium, means for causing variations of pressure upon said medium substantially corresponding to the variations of mechanical resistance to compression offered by said medium, an armature associated with 130

- said means, and a voltage-responsive electromagnet co-acting with said armature.
18. Regulating apparatus comprising, in combination, a pressure-controlled variable 5 resistance medium resisting mechanical pressure at an increasing rate as compression progresses, means for exerting pressure upon said medium at an increasing rate as compression progresses, and electro-magnetic 10 means controlling said last named means to cause changes of resistance in said medium substantially proportional to changes of current in said electromagnetic means.
19. Regulating apparatus comprising, in combination, a pressure-controlled variable 15 resistance medium, means adapted to cause variations of pressure upon said medium corresponding to the variations of mechanical resistance to compression offered by said 20 medium, an armature associated with said means, and an electromagnet co-acting with said armature to hold said medium at a given stage of compression with a given current passing through said magnet.
20. Regulating apparatus comprising, in combination, a resistance device exerting an increasing mechanical opposition to force tending to decrease its value, means for exerting pressure upon said medium to compensate for the effect of said mechanical opposition, and electromagnet means for controlling said compensating means.
21. In regulating apparatus, in combination, a pressure-controlled variable resistance 35 medium comprising a plurality of contacting members, adjustable means adapted to adjust the range of compression of said medium, a shunt circuit about said members, and electrically operated means comprising 40 a toggle adapted to increase pressure upon said members as the toggle approaches its central position and close said shunt as the compression approaches completion.
22. In regulating apparatus, in combination, a pressure-controlled variable resistance medium, means adapted to lead current therethrough, current taps disposed in said medium at intervals in the direction of flow of current, electrical connections to said 45 taps, and electromagnetic means controlling the pressure upon said medium and the connections to said taps.
23. In regulating apparatus, in combination, a pressure-controlled variable resistance 55 medium, and electromagnetic means controlling the pressure upon said medium, said means comprising means adapted to successively eliminate sections of said medium.
24. In regulating apparatus, in combination, a pressure-controlled variable resistance medium, and electromagnetic means controlling the pressure upon said medium, said means adapted to successively shunt 60 sections of said medium.
25. In regulating apparatus, in combination, a pressure-controlled variable resistance medium, a pair of members of relatively low resistance disposed in said medium intermediate its ends, means adapted to bring said members into low resistance connection at an advanced stage of compression of said medium and short-circuit the intervening resistance members, and electromagnetic means controlling the pressure 70 upon said medium.
26. In regulating apparatus, in combination, a pressure-controlled resistance medium, a series of members of relatively low resistance disposed at intervals in said medium, means adapted to bring said members into low resistance connection at an advanced stage of compression of said medium, and electromagnetic means controlling the pressure upon said medium.
27. In regulating apparatus, in combination, a pressure-controlled resistance medium, a series of members of relatively low resistance disposed within said medium, means adapted successively to bring said 80 members into low resistance connection at an advanced stage of compression of said medium, and electromagnetic means controlling the pressure upon said medium.
28. In regulating apparatus, in combination, a pressure-controlled resistance medium, a pair of members of relatively low resistance disposed within said medium, and electromagnetically controlled means comprising a toggle adapted to compress said 85 medium and bring said members into low resistance connection as the toggle approaches its central position.
29. In regulating apparatus, in combination, a pressure-controlled resistance medium, a plurality of normally opened shunt circuits respectively disposed about successive portions of said medium, means adapted to shunt successively a greater portion of said medium, a toggle adapted to compress said medium, a member moved by said toggle to successively close said shunt circuits, and electromagnetic means controlling the 90 position of said toggle.
30. In regulating apparatus, in combination, a pressure-controlled resistance medium, a plurality of normally opened shunt circuits respectively disposed about successive portions of said medium, a toggle adapted to compress said medium, a member moved by said toggle to successively close said shunt circuits, the contacts of said shunt circuits being arranged to offer successively greater resistance to the movement of said toggle as the compression progresses, and electromagnetic means controlling the position of said toggle.
31. In regulating apparatus, in combination, a pressure-controlled variable resistance medium, a plurality of normally 130

opened shunt circuits respectively disposed about successive portions of said resistance, means adapted successively to close said shunts as the compression progresses and 5 electromagnetic means controlling the pressure upon said medium.

32. In regulating apparatus, in combination, a pressure-controlled variable resistance medium, a shunt circuit about said medium, and electromagnetically controlled 10 means adapted to compress said medium and close said shunt as the compression approaches completion, said means comprising a toggle which increases compression as it 15 approaches its central position.

33. Regulating apparatus for car-lighting systems comprising, in combination, a variable resistance exerting a variable physical opposition to force tending to vary its resistance value, means for exerting variable force upon said resistance substantially proportional to the variable physical opposition thereof, and electromagnetic means for controlling said first-mentioned means. 20

In testimony whereof I affix my signature, 25 in the presence of two witnesses.

JOSEPH BIJUR.
